Primary Examiner — Susan Moon Lee(74) *Attorney, Agent, or Firm* — Harness, Dickey & Pierce, P.L.C.(57) **CLAIM**

The ornamental design for a scanner, as shown and described.

DESCRIPTION

FIG. 1 is a perspective view of a scanner, as viewed from the top, front and right side, embodying our new design; FIG. 2 is a perspective view thereof, as viewed from the top, rear and left side;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines and portions contained within broken line shown within the square opening on the side of the scanner in FIGS. 1 and 6 are not claimed.
